A. WHITTEMORE

Machine for Manufacturing Sheet Cards.

Patented June 5, 1797.

June 5 1791

The Subdall referred to in their Letter Patent and marking, part of the same, containing a description in the words of the said Amos Whitfield himself, of an improvement in manufacturing cards.

A general specification of a machine for manufacturing, sheet-cards, suitable for wool or cotton cardy, fullers cardy, clothsed part, & cardy of every kind, size & description. This machine is put in motion by a cylinder, on which are a number of knobs to give the different motions. This cylinder may be turned by hand or other power. On one end of the cylinder is a balance wheel with two, or, more knobs in one of the arms is a handle to turn it, on the other end is a sector wheel which plays into a pinion which turns two rollers, which roll the wire into the form of the proper lengths immediately after a corner (so called) is let off by a shoe on the cylinder, and, forced up by a spring against the shoe, so rolled into the form, and holds it against the head, while the shear forced up by another knob, cuts the wire off. A pricker is forced up by another knob, & pricks two holes in the leather and falls back while the wings forced up by another knob from the wire into a staple. Around the head, a conductor is let off by a shoe in the cylinder and is forced up by a spring to its proper place to conduct the wire or staple into the leather, which is held in the carriage and extended by cords so as to tight. Immediately the whole apparatus for forming the wire is forced forward and places the wire or staple into the leather and holds it until the worker, which is on the other side of the leather, and moved by another knob, forces the point of the wire or staple down onto a stamping piece placed the same side of the leather with a stroke, which completes the wire immediately. The head is lifted up by another knob, the former advances further forward and sets the wire conductor to the leather then the apparatus which forced the wire, and worker falls back to their place and leaves another wire while the wire is rolling into the form, the carriage is moved by a wheel taking one work up to the back, which is moved by another knob.

the knob on the cylinder, and moves the carriage and leather to cover another wire or staple, it continues on until it goes meeting the card or sheet lengthwise. The instant this dog is raised and held up by a piece which is governed by a spring, and a straight piece which gives the length of the card or sheet, another dog at the opposite end of the machine falls into another toothed rack, moves the carriage and sheet back in the same manner it was carried forward; this dog is moved by the same knob, which moves the first mentioned dog, by being connected with it at the same time that dog shifts another dog which is moved by a small wheel on the end of the cylinder, being connected with a piece, which falls into a slot or space in the small wheel, by which means the dog takes one tooth in a rag wheel, which is placed on an arbor about the small wheel, on which arbor are two small wheels, on which are two chain or straps, which are confined to the carriage or pieces which the carriage slides on; the piece connected with the dog, rises immediately and the small wheel on the first mentioned arbor, revolves round, and forces the dog to move the rag wheel, and winds the chain or strap, which raises the carriage and leather sufficiently for another row of wire to be laid; it holds the rag wheel in the same place until the row of wire is full; this piece which is connected with the dog which moves the rag wheel is also connected with another piece, on which it which rests and slides on a straight piece, the same length of the straight piece that gives the length of the card or sheet, and governs the other two dogs; this piece is connected with the dog, which slides on the straight piece as the carriage is moved on and the straight piece being confined to the carriage until it slips off the end of the straight piece, and lets the piece above connected with it and the dog fall into the blank or space in the small wheel on the first mentioned cylinder, to let the dog take one tooth in the rag wheel and using again by the small wheel revolving around it catches on the straight piece, and held up until the row of wire is full and then slips off the other end, continues to operate in the same manner until it

card or sheet is completed, or has the complement of nine, let us say, two or more cards or sheets may be set at the same time in the ~~stack machine~~ by the addition of a former to each sheet or card.
